(57) **CLAIM**

The ornamental design for a cable connector, as shown and described.

DESCRIPTION

FIG. 1 is a front, top, left-side view of the cable connector;

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in the drawings depict portions of the cable connector that form no part of the claimed design.
